THERMAL CONTROL DEVICE

George R. Townsend, Schenectady, N. Y., assignor to General Electric Company, a corporation of New York

Application April 1, 1938, Serial No. 199,366

11 Claims. (Cl. 200—113)

My invention relates to thermal control devices, more particularly to temperature responsive control devices for controlling an electric circuit in response to changes in temperature, and has for 5 its object the provision of a reliable and effective device of this character which is sensitive and quick acting, and which is adjustable for either automatically or manually resetting the control means.

10 In controlling an electrical circuit in response to changes in temperature to prevent over-heating or over-loading, the chief problem involved is in opening and closing the circuit quickly without detrimental arcing at the contacts. It is also 15 desirable that the switch be operable by a small temperature change for providing high sensitivity. In carrying out my invention, I have provided a device whose parts are in a definite relationship with each other to obtain the required snap 20 action. The principle of operation is based on a combination of a bimetallic strip having a definite spring gradient working against an opposing force having a somewhat steeper gradient. This 25 opposing force consists of the bias of a leaf spring operating through suitable leverage plus the tip pressure of a movable contact. When heat is applied to the bimetallic strip, a force is built up which finally is sufficient to overcome the opposing forces. At this point the switch starts to 30 operate. The force of the bimetallic strip decreases in value as the switch opens, but the opposing force decreases faster, and the switch arrives at its open position with the bimetallic force slightly greater than the opposing forces. 35 When the bimetallic strip is cooled sufficiently to reduce its force by this amount, the opposing force becomes stronger and the switch will start to close again. As the switch closes, the opposing force increases at a faster rate than the bimetallic 40 force, and the switch arrives in its closed position with its opposing forces slightly greater than the bimetallic force.

45 For a more complete understanding of my invention, reference should be had to the accompanying drawing, Fig. 1 of which is an elevation view of a switch embodying my invention with the cover plate removed from the casing having its contacts closed and its bimetallic element in a normal unheated position; Fig. 2 shows an elevation view partly in section with the switch opened to its automatic reset position; Fig. 2 shows an elevation view with the switch having a portion of the cover plate removed opened to its manual reset position; Fig. 4 is a side elevation view of 50 Fig. 3 partly in section; Fig. 5 is a side elevation

view of Fig. 2 partly in section; Fig. 6 shows an elevation view of a constructional detail of a portion of the reset mechanism; Fig. 7 is a perspective view of some of the members comprising the snap mechanism. 5

Referring to the drawing, I have shown my invention in one form in the various views as applied to a thermal over-load snap action relay, although it is to be understood that this invention has general application to thermal control devices. As shown in Fig. 2, the control device comprises a casing 10 of any suitable insulating material provided with a cover plate 11 and a fastening rivet 12 therefor (shown in Fig. 3) which extends through the cover plate 11 into a hole 13 15 in a thickened portion of the casing 10 for holding the cover plate 11 in position. Extending downwardly through an opening 14 in the top of the casing 10 is a heating element 15 in the form of a helical resistance wire which is supported 20 by the screws 16 and 17 threaded into the top of the casing 10 on either side of the hole 14. The heating element 15 is connected in series with the terminals 18 and 19 having the screws 20 and 21 25 adapted to secure the wires of a circuit (not shown) which will heat the element 15.

At the side of the casing 10, mounted on a projection 22 of insulating material which may be integral with the casing 10 are the terminals 23 and 24 which may be separated by a fin of 30 insulating material 25. The terminals each have appropriate fastening means, such as screw 26, to firmly hold the wires of the incoming circuit which is to be completed or broken responsive to the heating of the element 15. The terminals 23 35 and 24 extend through appropriate openings into the inner portion of the casing 10 and carry therein the resilient strips 27 and 28 which are formed of copper or other suitable resilient conducting metal and have fastened at their lower 40 ends the contacts 29 and 30 which are normally held in pressure engagement by the strips 27 and 28. The resilient strips 27 and 28 may be fixed at the terminals 23 and 24 by any suitable means such as by welding or riveting, and the contacts 45 29 and 30 may be fastened to the strips 27 and 28 in a like manner.

Spaced apart a short distance from the heating element 15 and also extending downwardly into the casing 10 is a thermoresponsive member 50 in the form of a bimetallic element 31 which is made of two strips of metal having dissimilar coefficients of expansion, such as invar and steel, the strips being securely pressed or welded together lengthwise. The bimetallic element 31 may 55

be somewhat triangular in shape having its broad end fixed securely at the top of the casing 10 by welding or brazing to the terminal strip 18 which extends over to the opening 14 and is bent downwardly to hold the bimetallic element 31. The lower portion of the bimetallic element 31 is free to deflect in response to the changes in temperature which occur in a manner dependent upon the current flowing in the heating element 15.

10 Normally, the bimetallic element 31 in its unheated condition is a straight strip, as seen in Fig. 1, which will deflect positively to the left with an appropriate rise in temperature in a manner best illustrated in Fig. 3.

15 The lower end of the bimetallic element 31 is loosely connected to a pivoted member 32 by a link 33 adapted to impart to the pivoted member 32 the force of the element 31 when the latter deflects in a positive direction, i. e., from right to left. The pivoted member 32, best illustrated in Fig. 7, may be a flat metallic stamping having a projection 34 at its upper end with a pair of shoulders 35 and 36 on either side thereof, the projection 34 being adapted to fit into an appropriate opening 37 in one face of a supporting bracket 38. The bracket 38 may be an L-shaped stamping having a hole 39 in its other face arranged to receive a rivet 40 for holding the bracket in a fixed position at the upper left-hand corner in the interior of the casing 10 over a thickened portion of the casing wall. It may be here noted that the rivet 40 has an eccentric body portion just under its slotted head for making a factory adjustment of the position 35 of the bracket 38. This is best shown in Fig. 2 where it is seen that the eccentric portion of the rivet 40 is holding the bracket 38 in a position to the right for adjusting the pivoted member 32 in a proper relation with bimetallic strip 40 31 and the floating link 49 for snap operation at a predetermined temperature. After the proper adjustment is made, the end of the rivet 40 is peaned over as shown in Fig. 6. The pivoted member 32 will move pivotally on the edges of 45 the shoulders 35 and 36 which ride on the bottom of the bracket 38. The link 33 may be another metallic stamping having the projecting portions 41 and 42 at each end adapted to fit loosely into rectangular openings in the bimetallic element 31 and the pivoted member 50 32 (the rectangular opening 43 in the pivoted member 32 is shown in Fig. 7). The loose link 33 causes the pivoted member 32 to receive the force of a positive deflection of the bimetallic element 31, but when the bimetallic element 31 is caused to deflect negatively by a reduction in its temperature, no pull is exerted on the pivoted member 32, since the bimetallic element 31 is free to slide from left to right along the projection 42 of the link 33.

60 Rigidly mounted in the base of casing 10 by a threaded screw 44, a nut 45, and a washer 46 is a leaf spring 47 which is fixed at its right end and has its left end positioned to deflect 65 in the direction of the pivot point of the pivoted member 32. The spring 47 has a slot 48 at its left end running longitudinally of the spring and a bent-over portion at its left end which includes a portion of the slot 48, so that the slot 70 48 runs in the two planes of the spring 47. For imparting the force of the spring 47 to the pivoted member 32, a floating link 49 is provided having the V-shaped notches 50 and 51 at its upper and lower ends, which are adapted to fit into a notch 52 at the lower end of the

pivoted member 32 and the slot 48 of the spring 47, respectively. Connecting the pivoted member 32 and the resilient contact strip 27 is a lost motion link 53 which is formed of a suitable insulating material and is adapted to permit a slight positive movement of the pivoted member 32, before the motion is carried to the resilient strip 27 for disengaging the contacts 29 and 30. The link 53 is slidable on the upper faces of the supports 54 and 55 which may be integral with the bottom of the casing 10.

Extending from the lower end of the pivoted member 32 is a projection 56 which cooperates with a slidable stop member 57 on the left inside wall of the casing 10, to limit the movement of 15 pivoted member 32 in the automatic reset position (shown in Fig. 2) or the manual reset position of the switch (shown in Fig. 3). The slidable member 57 is mounted between the left wall of the casing 10 and a guide projection 58 20 extending outwardly from the back wall of the interior of the casing 10, and comprises a flat metal bar having an off-set portion at its upper end carrying at the end thereof, above the casing 10, a handle 59 of suitable insulating material. 25 The off-set portion of the slidable member 57 extends through an opening in the upper portion of the casing 10 and through a guide collar 60 formed in the metal terminal 18. Along the rear edge of the off-set portion of the slidable member 57 is a hook-shaped projection 61 30 extending through an opening 62 in the rear wall of the casing 10. The projection 61 is adapted to cooperate with the free end of a straight wire spring 63 to hold the slidable member 57 in either of two positions, the spring 63 being securely riveted at its other end to the casing 10 by a rivet 64. When the wire spring 63 is placed beneath the projection 61 (shown in Fig. 4), it will bias the slidable member 57 in 40 an upper position, so that the projection 56 on the pivoted member 32 will contact the left wall of the casing 10 in the manual reset position of the switch. When the switch is in its manual reset position, the handle 59 may be depressed 45 to cause the lower end of the slidable member 57 to contact the projection 56 on the pivoted member 32, for forcing the switch beyond its dead center position to enable it to snap to a closed position. When the wire spring 63 is placed on 50 the top of the projection 61 in the hook thereon (shown in Fig. 5), it will bias the slidable member 57 to its lower position, so that the projection 56 on the pivoted member 32 will contact the slidable member 57, now interposed between 55 it and the left wall of casing 10, to prevent the switch from passing its dead center position and limit it to the automatic reset position.

In operation, the switch is normally positioned as illustrated in Fig. 1. The contacts 29 and 30 60 are closed and held in pressure engagement by the resilient strips 27 and 28, and the bimetallic element 31 is in an unheated and undeflected condition. The leaf spring 47 is exerting a force 65 through the floating link 49 which tends to rotate the pivoted member 32 in a counter-clockwise direction. When an excessive current passes through the heating element 15, heat will be radiated to the bimetallic element 31. Thereupon, the bimetallic element 31 will build up a 70 force tending to deflect it in a positive direction to the left; this force will act through the link 33 against the pivoted member 32 and will tend to rotate the pivoted member 32 in a clockwise direction. When this force becomes sufficient to

overcome the opposing force of the leaf spring 47, the pivoted member 32 and the bimetallic element 31 will start to move to the left. As the bimetallic element deflects to the left, the force it exerts decreases at a given rate. The force of the spring 47 on the pivoted member 32 also decreases, since the leverage of the floating link 49 changes as the link approaches its dead center position, and at dead center there is no rotational force on the pivoted member 32 from the spring 47. It should be noted, however, that the force of the spring 47 tending to rotate the pivoted member 32 decreases at a faster rate than the force of the bimetallic element 31. After a short initial movement of the pivoted member 32, it picks up the tip pressure load of the resilient strip 27, and this load adds to the forces opposing the force exerted by the bimetallic element 31. The decreasing force of the bimetallic strip 31 is still sufficient to overcome the decreasing opposing forces, and there is a snap movement of the pivoted member 32 to its automatic reset position, and the contacts 29 and 30 open as shown in Fig. 2. In this position, the projection 56 and the slidable member 57 which is held down by the wire spring 63 cooperate to prevent the floating link 49 from passing its dead center position under the pivoted member 32. Therefore, the spring 47 still exerts a small force on the pivoted member 32 which tends to rotate this member in a counter-clockwise direction against the superior force exerted by the bimetallic element 31.

As soon as the heating element 15 cools down, as it will do, if its circuit is connected to include the contacts 29 and 30 which are now opened, the bimetallic element 31 will also cool sufficiently to decrease its bias on the pivoted member 32 by an amount slightly greater than the differential of force which was holding the pivoted member in the last mentioned position. Immediately, the predominating force of the spring 47 will begin to move the pivoted member 32 in a counter-clockwise direction, and with this motion, the spring force on the pivoted member 32 will increase at a faster rate than the force of the bimetallic element 31, to cause the pivoted member to snap to its original position and enable the contacts 29 and 30 to close by the pressure of the resilient strips 27 and 28.

When the switch operates as just described, it is considered as self-resetting, or automatic resetting. For some applications it may be necessary that the mechanism does not reset itself, but that it stay open until reset manually. In such a case, the slidable member 57 may be biased to the position shown in Fig. 3 and Fig. 4, by placing the wire spring 63 beneath the projection 61. When the switch is actuated by the bimetallic element 31, its snap movement will carry the pivoted member 32 over the dead center position of the floating link 49, and the projection 56 will contact the left wall of the casing 10, leaving the contacts 29 and 30 open until the switch is manually reset. To reset the switch, the slidable member 57 may be depressed by pressing down on the handle 80. The end of the slidable member 57 will engage the projection 56 and force the pivoted member 32 an appreciable distance over its dead center position to cause the switch to snap to its closed position and permit the contacts 29 and 30 to close.

While I have shown a particular embodiment of my invention, it will be understood, of course,

that I do not wish to be limited thereto since many modifications may be made, and I therefore contemplate by the appended claims to cover any such modifications as fall within the true spirit and scope of my invention.

What I claim as new and desire to secure by Letters Patent of the United States, is:

1. A thermally actuatable switch comprising a thermoresponsive element adapted for movement in response to changes in temperature, switching means, means including a pivoted member movable by the force of movement of said thermoresponsive element, a spring, means including a link intermediate said spring and said pivoted member for imparting a snap action to said pivoted member after a predetermined movement of said pivoted member by the force of movement of said thermoresponsive element, and means operable by said pivoted member for actuating said switching means.

2. A thermally actuatable switch comprising a bimetallic element arranged for lateral deflection in response to changes in temperature, switching means, a pivoted member movable by the force of deflection of said bimetallic element, means including a link connecting said pivoted member and said bimetallic element for causing the movement of said pivoted member by a deflection in only one direction of said bimetallic element, a spring, means including a second link intermediate said spring and said pivoted member for imparting a snap action to said pivoted member after a predetermined movement of said pivoted member by the force of deflection of said bimetallic element, and means operable by said pivoted member for actuating said switching means.

3. A thermally actuatable switch comprising a bimetallic element fixed at one end for lateral deflection in response to changes in temperature, switching means, a member mounted on a fixed pivot point for pivotal movement by a deflection of said bimetallic element, a leaf spring fixed at one end and positioned to impart a maximum component of force toward said pivot point, a floating link intermediate said spring and said pivoted member for imparting a snap action to said pivoted member upon a predetermined deflection of said bimetallic element, and means operable by said pivoted member for actuating said switching means.

4. A thermally actuatable switch comprising a bimetallic element fixed at one end for positive deflection in response to a rise in temperature, switching means including a plurality of contacts, means including a pivoted member movable by the force of said positive deflection of said bimetallic element, a spring, a link intermediate said spring and said pivoted member positioned to impart a force from said spring opposing said positive deflection force on said pivoted member which decreases at a faster rate than said deflection force for giving a snap action to said pivoted member upon a positive deflection of said bimetallic element, and means operable by said pivoted member for moving said contacts apart.

5. A thermally actuatable switch comprising a bimetallic element fixed at one end for positive and negative deflection in response to changes in temperature, switching means including a plurality of contacts, a pivoted member movable by a positive deflection of said bimetallic element, a spring, a floating link intermediate said spring and said pivoted member to impart a snap action to said pivoted member from a first position to

a second position upon a positive deflection of said bimetallic element, means including a stop for preventing said floating link from passing its dead center position for causing a snap return 5 of said pivoted member from said second position to said first position upon a negative deflection of said bimetallic element, and means operable by said pivoted member for actuating said switching means.

10 6. A thermally actuatable snap switch having a pivoted member, a bimetallic element fixed at one end for a positive and negative deflection in response to changes in temperature, linking means intermediate said bimetallic element and said 15 pivoted member for causing a positive pivotal movement of said pivoted member in response to a positive deflection of said bimetallic element, a spring, a floating link intermediate said spring and said pivoted member to impart a snap action 20 to said pivoted member from its first position to a second position upon a predetermined positive deflection of said bimetallic element, stop means including a projection on said pivoted member and a member slidable to engage said 25 projection for preventing said floating link from passing its dead center position for causing a snap return of said pivoted member to its first position upon a predetermined negative deflection of said bimetallic element, and switching 30 means operable by said pivoted member.

7. A thermally actuatable snap switch having a pivoted member, a bimetallic element fixed at one end for a positive and negative deflection in response to changes in temperature, linking 35 means intermediate said bimetallic element and said pivoted member for causing a positive pivotal movement of said pivoted member in response to a positive deflection of said bimetallic element, a spring, a floating link intermediate 40 said spring and said pivoted member to impart a snap action to said pivoted member from its first position to a second position upon a predetermined positive deflection of said bimetallic element, stop means including a projection on said 45 pivoted member and a member slidable to engage said projection for preventing said floating link from passing its dead center position for causing a snap return of said pivoted member to its first position upon a predetermined negative 50 deflection of said bimetallic element, switching means including a plurality of contacts, and means including a link operable by said pivoted member for actuating said switching means.

8. A thermally actuatable switch comprising a 55 casing of insulating material containing a bimetallic element fixed at one end for positive and negative deflection in response to changes in temperature, switching means, a pivoted member movable by a positive deflection of said bimetallic 60 element, a spring, a link intermediate said spring and said pivoted member to impart a snap action to said pivoted member upon a positive deflection of said bimetallic element, means operable by 65 said pivoted member for actuating said switching means, and means including a member slidably mounted in said casing having a handle portion projecting therefrom, said slidable mem-

ber being arranged to engage said pivoted member for manually resetting said switch after a sufficient negative deflection of said bimetallic element.

9. A thermally actuatable switch comprising a 5 bimetallic element fixed at one end for lateral deflection in response to changes in temperature, switching means, a pivoted member movable by a deflection of said bimetallic element, a spring, a link intermediate said spring and said pivoted 10 member for imparting a snap action to said pivoted member upon a predetermined deflection of said bimetallic element, means operable by said pivoted member for actuating said switching means, means including a member slidable to two 15 positions adapted for manually resetting said switch, and spring means for biasing said slidable member to the first of said positions for causing automatic resetting of said switching means by limiting the movement of said pivoted member, said spring means being further adapted for biasing said slidable member to the second of said positions for enabling manual resetting of said switch.

10. A thermally actuatable snap switch having a 25 manual reset position and an automatic reset position comprising a bimetallic element fixed at one end for positive and negative deflection in response to changes in temperature, switching means, means including a pivoted member adapted 30 for movement by said positive deflection of said bimetallic element, a leaf spring, a link intermediate said spring and said pivoted member for imparting a snap action to said pivoted member upon a positive deflection of said bimetallic element, means operable by said pivoted member for actuating said switching means, means including a member slidable to two positions 35 adapted for manually resetting said switch, and spring means comprising a straight wire 40 spring fixed at one end with its free end adapted for biasing said slidable member to the first of said positions for causing automatic resetting of said switching means by limiting the movement of said pivoted member, said spring means 45 being further adapted for biasing said slidable member to the second of said positions for enabling manual resetting of said switch.

11. A thermally actuatable switch comprising a bimetallic element fixed at one end for positive 50 deflection in response to a rise in temperature, switching means including a plurality of contacts, means including a pivoted member movable by the force of said positive deflection of said bimetallic element, a spring, a link intermediate 55 said spring and said pivoted member positioned to impart a force from said spring opposing said positive deflection force on said pivoted member, which decreases at a faster rate than said deflection force for giving a snap action to said pivoted member upon a positive deflection of said bimetallic element, and means including a lost motion link intermediate said pivoted member and said switching means for actuating said switching means after a predetermined positive 60 movement of said pivoted member.

GEORGE R. TOWNSEND.
